(57) CLAIM

The ornamental design for a curette body, as shown and described.

DESCRIPTION

FIG. 1 is a top view of a curette body showing my design, the bottom view being a mirror image thereof;

FIG. 2 is a right side view thereof, the left side being a mirror image thereof;

FIG. 3 is an end view of the left end of the curette; and,

FIG. 4 is an end view of the right end of the curette.
The broken lines shown in FIGS. 1–4 represent unclaimed subject matter.
